UNITED STATES PATENT OFFICE.

ROBERT DUNNING, OF BUFFALO, NEW YORK.

TROLLEY-WIRE CLEANER.

SPECIFICATION forming part of Letters Patent No. 638,047, dated November 28, 1899.

Application filed March 14, 1899. Serial No. 708,986. (No model.)

To all whom it may concern:

Be it known that I, ROBERT DUNNING, a citizen of the United States, residing at Buffalo, in the county of Erie and State of New York, 5 have invented new and useful Improvements in Trolley-Wire Cleaners, of which the following is a specification.

This invention relates to the scrapers or cleaners which are applied to the trolley-head 10 of an electric car for removing sleet and ice from the trolley-wire or conductor in winter.

My invention has for its object to provide a scraper of this kind which can be readily attached to the head of the trolley-pole without requiring the removal of the trolley-wheel, 15 which is firmly held against displacement and which presents effective scraping-surfaces.

In the accompanying drawings, Figure 1 is a side elevation of the head of a trolley-pole 20 having my improved scraper applied thereto. Fig. 2 is a longitudinal central section of the parts. Fig. 3 is a top plan view thereof. Fig. 4 is a fragmentary transverse section, on an enlarged scale, in line 4 4, Fig. 1, the trolley-wire being omitted. Figs. 5 and 6 are similar sections in lines 5 5 and 6 6, Fig. 1. Fig. 7 is a central longitudinal section of the trolley-head and the scraper, showing a modified construction of the scraper.

Like letters of reference refer to like parts in the several figures.

A is the trolley-wire, and B the trolley-wheel, journaled in the fork or bifurcated head C of the trolley-pole C'. The head C has the usual 35 socket C² for attaching the same to the pole.

D is my improved scraper, which is adapted to be attached to the head of the trolley-pole and to run against the under side of the conductor A. This scraper consists of a curved 40 concavo-convex plate or shoe which covers the upper and the front portions of the trolley-wheel and which is curved to conform to the periphery of the wheel. The convex rear side of the scraper extends into the groove of 45 the trolley-wheel, while on its concave outer side it is provided with outwardly-extending side flanges d for retaining the scraper in contact with the conductor. The scraper is removably attached to the head of the trolley- 50 pole by a clamp or fastening of any suitable construction. Its lower portion or shank d'

is arranged between the jaws of the trolley-head and preferably pivoted by a transverse pin e to a bracket or plate E, which is removably secured to the under side of the socket 55 C² of the trolley-head by a screw f. This pivotal connection permits the upper free portion of the scraper to swing toward and from the periphery of the trolley-wheel and adjust itself within certain limits to wheels of different diameters.

g represents raised scraping-ribs arranged transversely in the groove or concave outer side of the scraper and having sharp upper edges which are adapted to run against the 65 under side of the conductor for scraping off any sleet or ice adhering thereto. The sharp edges of these scraping-ribs are provided centrally with curved depressions g', which conform to the under side of the conductor. 70 These scraping-ribs may be cast integral with the scraper, as shown in Fig. 7; but they are preferably removable, so that they can be sharpened when dull or be replaced by new ones when worn out. In the construction 75 shown in Figs. 2, 3, and 5 of the drawings the ribs are seated at their lateral edges in radial grooves or ways h formed in the inner sides of the flanges d of the scraper and are secured therein by radial screws i, passing 80 through openings formed in the bottom of the scraper and entering openings formed in the inner edges of the scraping-ribs, as shown in Figs. 2 and 5. The inner sides of the flanges d preferably converge inwardly or toward the 85 periphery of the trolley-wheel, and the lateral edges of the scraping-ribs are correspondingly beveled, as shown in Fig. 5, so that the ribs are tightly wedged between the flanges of the scraper upon tightening the screws i. As 90 shown in the drawings, the side flanges d extend outwardly beyond the scraping-ribs, so that when the scraper bears against the conductor the flanges stand on opposite sides of the conductor and retain the scraper against 95 the same. The scraping-ribs are arranged at suitable intervals, and a sufficient number of the same is employed—say three, as shown—so that one or two ribs are presented to the conductor in all positions assumed by the 100 trolley-head. These flanges are provided near the bottom of the scraper with a num-

ber of openings *j* for the escape of any detached ice or sleet that may drop between the scraping-ribs, thereby preventing the ice and sleet from packing between the ribs and forming a practically smooth bearing-surface with the same.

k represents vertical retaining lips or lugs formed on the side flanges of the scraper *D* at or near the front and rear ends thereof and overlapping or embracing the grooved rim of the trolley-wheel. These lugs hold the upper portion of the scraper against lateral displacement on the trolley-wheel and relieve its pivot *e* from the side strains to which the scraper is subjected.

l is a lip or shelf which is arranged on the lower front portion of the scraper *D* and extends forwardly over the upper side of the attaching-socket *C*² of the trolley-head. This shelf sheds any falling ice or sleet from the joint or gap between the scraper and said socket.

When the scraper is applied to the trolley-head, it rests loosely against the grooved rim of the trolley-wheel, the scraper being held in place against the wheel by the upward pressure produced by the spring of the trolley-pole.

In the modified construction of the scraper shown in Fig. 7 the same is rigidly secured to the trolley-head by the screw *f*, which passes through a lug *m* formed at the lower end of the scraper-shank and bearing against the under side of the attaching-socket *C*².

In both of the constructions shown the scraper can be quickly detached from the trolley-head by simply removing the screw *f*, and when the scraper is removed the trolley-wheel is free to run against the conductor like an ordinary trolley-wheel.

I claim as my invention—

1. A scraper adapted to be attached to a trolley-head and consisting of a plate of concavo-convex cross-section which is curved to conform to the periphery of the trolley-wheel and provided in its grooved or concave face with a transverse scraper rib or ribs and in the walls of said groove with openings for the escape of sleet and ice, substantially as set forth.

2. A scraper adapted to be attached to a trolley-head and consisting of a curved plate or shoe adapted to extend over the upper portion of the trolley-wheel and provided in its outer face with a longitudinal groove and a transverse scraping rib or ribs removably secured in the groove of the scraper, substantially as set forth.

3. A scraper adapted to be attached to a trolley-head, and consisting of a curved plate or shoe adapted to extend over the upper portion of the trolley-wheel and provided in its outer face with a longitudinal groove provided in its side walls with ways which extend from the outer edge of said walls to the bottom of the groove, removable scraping-ribs arranged in said ways, and a fastening for retaining the ribs in place, substantially as set forth.

Witness my hand this 10th day of March, 1899.

ROBERT DUNNING.
